UNITED STATES PATENT OFFICE.

CHARLES C. PRINZ, OF LOUISVILLE, KENTUCKY.

RECORD-CLEANER.

1,343,156.

Specification of Letters Patent.

Patented June 8, 1920.

Application filed April 21, 1919, Serial No. 291,517. Renewed April 30, 1920. Serial No. 377,978.

To all whom it may concern:

Be it known that I, CHARLES C. PRINZ, residing at Louisville, in the county of Jefferson and State of Kentucky, have invented new and useful Improvements in Record-Cleaners, of which the following is a specification.

This invention relates to talking machines, particularly to attachments therefor, and has for its object the provision of a record cleaner in the nature of a rotary brush driven by a spindle carrying the turn-table of the disk type of talking machine, whereby the brush will thoroughly clean the record during the playing thereof.

An important object is the provision of a cleaner of this character which may be slid into a casing or receptacle carried by the cabinet of a talking machine when the use of a brush is not desired.

Another object is the provision of a device of this character in which the rotary brush is mounted within a casing open at one side and provided with a rubber flap serving as a dust collector.

A further object is the provision of a cleaner of this character which is adapted for association with the drive spindle projecting through the turn table and which may be associated with the talking machine without making any appreciable alterations therein.

An additional object is the provision of a device of this character which will be very simple and inexpensive in manufacture, highly efficient in use, durable in service, and a general improvement in the art.

With the above and other objects and advantages in view, the invention consists in the details of construction to be hereinafter more fully described and claimed, and illustrated in the accompanying drawings, in which—

Figure 1 is a plan view of a talking machine having my device associated therewith,

Fig. 2 is a view on a larger scale showing a longitudinal sectional view through a portion of the talking machine and showing my device in position for cleaning a record,

Fig. 3 is a view similar to Fig. 2 showing my device moved out of engagement with the record and disposed within its housing,

Fig. 4 is a cross sectional view taken through the brush and its casing, and

Fig. 5 is a detail side elevation showing the upper end of the vertical housing,

Fig. 6 is a fragmentary plan view showing the rear end of the brush holding casing, 60 and

Fig. 7 is a fragmentary elevation of the upper end of the tubular housing taken at right angles to Fig. 5.

Referring more particularly to the drawings, the letter A designates the cabinet or body portion of a talking machine, within which is mounted the usual driven vertical shaft B which carries the turn table C and which projects above the top of the turn table. The record is designated by the numeral D. These parts are all portions of any of the various well known makes of talking machines known under various trade names and need no further description as they themselves form no part of the present invention.

In carrying out my invention I provide adjacent one side of the cabinet A, a vertically disposed tubular housing 10 which is provided in its sides with vertically extending slots 11 which are curved and laterally directed at their upper ends, as shown at 12. The tubular housing 10 is secured upon the cabinet in any desired manner, as for instance by means of threaded collars 13. This housing is also provided at its upper edge between the slots 11 with a recess 13a.

The numeral 14 designates a casing which is cylindrical in cross section except for an opening 15 at one side. This casing 14 has curved end walls 16 and 17 and is provided adjacent the end wall 16 with a lug 18 carrying laterally projecting studs 19 engaging within the slots 11 and their lateral branches 12 of the tubular housing 10. At one side, adjacent the opening 15, the casing 14 has secured thereon a strip 20 of rubber or other suitable flexible material which is adapted to serve as a dust collector, and which bears lightly upon the top of the record D when the device is in use.

Secured within the casing 14 at a point spaced from the end 17 is a bracket 21 including spaced arms 22 and journaled through these arms and through the closed end 16 of the casing 14 is a brush 23 having a shaft 24. At its end adjacent the end 17 of the casing 14, the shaft 24 carries a bevel gear 25 which meshes with a bevel gear 26 journaled in an extension of the bracket 21 and provided with an angular socket 27 adapted to be engaged upon the correspondingly formed projecting upper end of the spindle B which extends through the turn 115

table. Secured or formed upon the end 17 of the casing 14 is a handle 28 and also a lug 29.

In the operation of the device, when it is not desired to use the cleaner brush, the parts are disposed as shown in Fig. 3 of the drawings, that is the casing 14 with all its associated parts is disposed entirely within the tubular housing 10 and the studs 19 carried by the lug 18 of the casing 14 are disposed at the lower ends of the slots 11 in the housing 10. When it is desired to clean a record during the playing thereof, it is merely necessary that the operator grasp the handle 28 and pull upwardly upon the casing 14 to pull the casing 14 out of the housing 10, the studs 19 riding upwardly through the slots 11 and then being disposed in the lateral branches 12 at the upper ends thereof. After the casing 14 is thus pulled out of the housing 10, the casing is swung into a horizontal position, the lug 18 being disposed within the recess 13^a, as shown in Fig. 2, and the angular socket 27 on the gear 26 is engaged upon the angular upper end of the drive spindle B. When a record is then played, and is of course rotated with the turn table C, the brush 23 bearing upon the record D will then be rotated by virtue of the engagement of the gears 25 and 26, the direction of rotation of the brush 23 being such that the brush will exert a brushing action against the direction of movement of the record D. As the brush 23 is thus rotated, it will be obvious that it will very effectually clean the record during the playing thereof. In order that the brush might not injure the record in any way, it is preferable that it, the brush, be formed of camel's hair or other similar very soft material.

After the brush has been in operation for a considerable length of time and it is desired to remove the accumulation of dust upon the rubber or other strip 20, it is merely necessary that the operator grasp the handle 28 and lift the casing 14 in a vertical position and slide it into tubular housing 10, whereupon the accumulation of dust and the like in the casing 14 will slide along the same and fall out of the end 16 thereof and into the lower end of the tubular housing 10. When an appreciable accumulation of dust is formed in the lower end of the housing 10, in order to remove the same, it is merely necessary that the operator disconnect the collars 13 carried by the housing 10 and remove the housing bodily from the cabinet A, after which the accumulation may be quickly and easily removed.

From the foregoing description and a study of the drawing, it will be apparent that I have thus provided a very simple device whereby a record may be thoroughly

cleaned during the playing thereof so that any clogging of the grooves therein will be absolutely prevented, it being noted that the device may be quickly and easily elevated from operative to inoperative position and vice versa, depending upon the wishes of the operator.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:—

1. In combination with a talking machine including a supporting cabinet, a turn-table and a spindle for rotating the turn-table, a record cleaning device comprising a casing secured within the cabinet, a brush slidably connected with and disposed normally within said casing and movable to extend therefrom in engagement with a record disposed upon the turn-table, and means associated with said spindle for rotating said brush.

2. In combination with a talking machine including a cabinet, a turn-table, and a spindle for rotating the turn-table, a record cleaning device comprising a vertical casing disposed within the cabinet and having one end extending thereabove, a brush slidably connected with the casing and mounted upon a spindle and movable within said casing whereby to be disposed selectively therein or in engagement with a record upon the turn-table, and means connecting the spindle of the brush with the spindle of the turn-table whereby to effect rotary movement of the brush simultaneously with rotary movement of the turn-table.

3. In combination with a talking machine including a supporting cabinet, a turn-table and a spindle for rotating the turn-table; a record cleaning device comprising a vertically disposed casing disposed within the cabinet and having its upper end extending above the turn-table and open, a brush disposable within said casing and having a spindle slidably connected therewith, said brush being movable out of said casing whereby to be disposed in horizontal position above and in engagement with a record placed upon the turn-table, a shield member extending from the brush and connected with the spindle thereof, and inter-engaging means carried by the turn-table spindle and the brush spindle whereby to effect rotary movement of the latter during rotary movement of the turn-table, said means comprising intermeshing gears.

In testimony whereof I affix my signature.

CHARLES C. PRINZ.
